UNITED STATES PATENT OFFICE

WILLIAM PARKS, OF FRAZEYSBURG, OHIO

LATCH

Application filed August 29, 1930. Serial No. 478,726.

This invention relates to a latch designed primarily for use in connection with screen doors.

One of the objects of the invention is to provide a latch which can be stamped readily from sheet metal, can be produced cheaply and, when in position on a door or the like, will constitute an efficient means for fastening the door in closed position.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing the preferred form of the invention has been shown.

In said drawing:

Figure 1 is an elevation of a portion of a screen door secured in closed position by the latch constituting the present invention.

Figure 2 is a section on line 2—2, Figure 1.

Figure 3 is a view similar to Figure 2 showing the door unfastened.

Figure 4 is a perspective view of the latch member.

Figure 5 is a perspective view of the keeper.

Referring to the figures by characters of reference, 1 designates an attaching plate of sheet metal having an ear 2 extending laterally from one edge thereof, there being a stop flange 3 bent from the lower edge of the ear 2 and bearing at one end against the attaching plate 1 so as to hold the ear 2 at the proper angle relative to the plate 1. An opening 4 is formed in the attaching plate for the reception of a screw or the like by means of which the keeper can be attached to a door jamb J.

The latch consists of a small piece of sheet metal indicated at 5 preferably near one end with an opening for the reception of an attaching screw or the like. A flange 8 is extended laterally from the upper edge portion of the plate 5 and constitutes means for

stiffening the plate in the direction of its length and also serves as a finger piece whereby the latch can be lifted out of fastening position.

The latch plate 5 is adapted to be attached to a door D and, if desired, a spacing washer 9 can be placed therebetween. This latch is so located that when the door is shut the plate 5 will swing on to the stop flange 3 so as to be supported in lapped relation to the ear 2. With the parts thus located as shown, for example, in Figure 2, the door is held securely in closed position. When it is desired to open the door it is merely necessary to lift the finger piece or flange 8 whereupon the latch can be swung upwardly and backwardly away from its keeper as shown in Figure 3.

Both the latch and the keeper can be stamped readily from sheet metal and, obviously, can be produced at extremely low cost.

What is claimed is:

A device of the class described including an attaching plate, an ear extending at an angle therefrom, a stop flange projecting from the ear and having one end bearing against the attaching plate thereby to hold the ear against bending in one direction relative to the attaching plate, a latch plate, and a combined stiffening flange and finger piece extending longitudinally of the latch plate.

In testimony that I claim the foregoing as my own, I have hereto affixed my signature.
